UNITED STATES PATENT OFFICE.

ARABELLE M. STOVER, OF NEVADA CITY, CALIFORNIA.

CLOSURE FOR RECEPTACLES.

1,087,847.

Specification of Letters Patent. Patented Feb. 17, 1914.

Application filed June 2, 1911. Serial No. 630,742.

To all whom it may concern:

Be it known that I, ARABELLE M. STOVER, a citizen of the United States, residing at Nevada City, in the county of Nevada and State of California, have invented new and useful Improvements in Closures for Receptacles, of which the following is a specification.

This invention relates to closures for receptacles and to one designed particularly for use upon milk bottles or the like, and has for an object to provide a closure of pliable material such as tin foil which may be securely fitted to the bottle and which will adapt itself to any imperfections in the neck of the bottle and which will form a protective seal therefor to effectively prevent the entrance of foreign matter or water into the bottle after the application of the closure thereto.

In the drawing, forming a portion of this specification and in which like numerals of reference indicate similar parts in the several views:—Figure 1 is a vertical section through the bottle showing the application of the closure thereto. Fig. 2 is a plan view of the closure. Fig. 3 is a view similar to Fig. 1 showing a slightly modified form of the invention. Fig. 4 is a plan view of the modified form of the closure. Fig. 5 is a plan view of the bottle shown in Fig. 3.

The closure shown in Figs. 1 and 2 of the drawing comprises an inner layer of material 1 of wax paper or the like and an outer layer of material 2 such as tin foil or other such pliable material which may be readily folded and securely confined to the neck and arranged thereon so as to fill any imperfections in the bottle neck and thereby positively prevent the entrance of moisture into the bottle after the attachment of the closure thereto. The layer of material 1 is preferably of circular configuration, while the material 2 is preferably of square configuration and considerably larger so that the material 1 is arranged wholly within the area of the material 2.

In practice, the material 1 is adapted to be disposed in the neck of the bottle and to be engaged against the shoulder A, as shown in Fig. 1 of the drawing. The materials 1 and 2 are cemented together or otherwise suitably held to each other. The marginal edges of the material 2 are folded over the neck of

the bottle, at 3, where it may be manipulated 55 so as to fill in any cracks or other imperfections or vacancies in the neck of the bottle.

In the form of the invention shown in Figs. 3 to 5 inclusive, of the drawing, the outer piece of material 4 is substantially the 60 same as the material 2 in the preferred form of the invention. The inner piece of material 5 is provided at one corner with a tearing tab 6. The corner piece 7 of the material 4 extends slightly beyond the end of the 65 tearing tab 6 so that the tab will be entirely concealed thereby, as illustrated in Fig. 3 of the drawing. In this form of the invention the closure is applied to the bottle substantially in the same manner as that described 70 in the preferred form of the invention, care being exercised so as to impress the material at the sides of the tab 6. This will indicate to the user of the bottle the exact location of the tearing tab, as illustrated at 8 75 in Fig. 5 of the drawing. The user may then mutilate the outer material 4 of tin foil and grasp the tab 6 of the inner material 5. By drawing the tab upwardly and moving the same forwardly from the user the closure 80 may be mutilated so as to permit of its being readily removed from the bottle.

I claim:

As a new article of manufacture, a closure 85 for bottles, comprising an inner sheet of impervious material normally occupying a flat position, the said material being provided with a laterally extended tab, and an outer piece of material of tin-foil, the latter normally occupying a flat position and being 90 extended beyond the marginal edges of the inner material and being adapted to be exteriorly compressed by the finger against the walls of the neck of a vessel, whereby to seal the joint between the vessel and the closure and to denote the position of the tab of the inner material, said outer material being adapted to be destroyed at the sides of the tab, whereby the tab can be grasped between the fingers to permit the closure to be 95 100 removed from the vessel.

In testimony whereof I affix my signature in presence of two witnesses.

ARABELLE M. STOVER.
